ABSALOM G. SMITH, OF JERSEY CITY, NEW JERSEY.

Letters Patent No. 73,934, dated January 28, 1868.

IMPROVEMENT IN LANTERN.

The Schedule referred to in these Letters Patent and making part of the same.

Specification of certain Improvements in Lanterns invented by ABSALOM G. SMITH, of Jersey City, in the county of Hudson, and State of New Jersey.

The object of my invention is to produce a good and serviceable lantern, easy to fill, light, clean, and repair when necessary, and composed of the least possible number of pieces, and so secured together that they may be held in place firmly, and yet be easily detachable.

In order to accomplish these objects, my invention consists in forming around the base and top a lantern-glass an inward projecting flange, for the purpose of forming a deflector at the base, and strengthening both top and bottom; in securing the globe within the guard-frame by means of a spring-catch, operating in a groove or depression, or beneath a shoulder formed in the side of the globe; in securing the upper and lower bands to each other by means of the burner-shaft; in holding the movable oil-pot in place by means of a fastening bearing upon its top; in the combination described of the locking-spring and device for holding the parts in proper position; in the form of the L-shaped slot, by means of which the device which secures the oil-pot is locked; in the method of holding the burner in place; in the arrangement of the lower band of the guard-frame, the lower band of the lantern, and the bottom of the globe; in the construction and arrangement of the lower part of the lantern, the oil-pot, and burner-shaft, so that said shaft, when in place, shall be slightly sprung downward at its ends, and press down upon the burner and oil-pot, and thus keep them securely in place. In the accompanying drawings—

Figure 1 is a side elevation of my lantern without its bail or handle.

Figure 2 is a vertical central section of the same.

Figure 3 is a side elevation in detail of the guard-frame of the lantern.

Figure 4 is a side elevation in detail of the glass of the lantern.

Figure 5 is a similar view of the burner and shaft.

Figure 6 is a similar view of the oil-pot.

Figure 7 is a similar view of the bottom of the lantern.

Figure 8 is a plan view of the spring used to fasten the bottom of the lantern to the guard-frame.

Figure 9 is an elevation of the same.

Figure 10 is an elevation of the L-shaped slot in the lower band of the lantern, into which one end of the burner-shaft is inserted.

Figure 11 shows the manner of fastening the globe into the guard-frame.

Figure 12 is a detailed view of a portion of the bands and one end of the burner-shaft, with the locking-spring to hold the parts in place.

Figure 13 is a similar view of the bands, and the other end of the burner-shaft, on which the button or thumb-piece for turning said burner-shaft is set.

A is the wire-guard frame, to protect the glass, C, from injury. B is the base or bottom, containing the loose oil-pot G. E is the burner; F, the burner-shaft; H, the locking-spring; I, the catch-spring, to hold the glass in place within the guards.

The guard-frame A consists of several stout wires, e, bent in proper form, and secured at both ends to two parallel flanges of metal, b and c. The vertical wires e are strengthened and united by two or more horizontal strengthening wires, e'. The upper flange, c, of the guard-frame, is attached by suitable means to the top or cap d, which surmounts the lantern, and to the lower flange, b, is secured, by solder or otherwise, the band a, which I call the lower band, to distinguish it from a similar band placed at the top of the guard-frame in lanterns of somewhat different construction and operation.

The glass, C, is in the form represented in fig. 4, being the form which I prefer. At top and bottom I form inward-projecting annular flanges, l and m, for the purpose of strengthening those parts, and rendering them less liable to injury by crashing than heretofore. The lower flange, m, in addition to the increase of strength which it imparts to the bottom edge of the globe, enables me to secure a broad, flat, deflecting surface, as shown in fig. 2, to catch and deflect the upward currents of air toward the base of the burner, without the aid of a metal rim attached to the bottom of the glass. In order to secure the proper deflection of the upward currents,

It is necessary that the lower edge of the glass, C, should be placed very near to the top of the oil-pot G; and I therefore insert the lower edge of the globe into the band h, which forms wall of the base or bottom, B, as shown in fig. 2, and am thus enabled to adjust it any desired distance above the edge of the oil-pot, as set forth.

It is required that the glass should be secured to the guard-frame, so that when the base, B, is removed, for the purpose of lighting the lamp or otherwise, the glass shall not be detached also, and yet it should be so secured as to be easily detached and removed, when required, for the purposes of cleansing or repair. I secure these qualities by forming a shoulder on the side of the glass, preferably near its lower end, under which a spring-catch engages when the glass is placed in position within the guard. This shoulder is formed by making an indentation in the glass, and this indentation I prefer to make in the form of an annular groove, j, because the spring-catch will then engage properly, without reference to the portion of the globe presented. This would not be the case if the indentation should be confined to one point. Lantern-glasses have heretofore been secured within the guard-frame by means of a bayonet-joint fastening, consisting of a projection, commonly made on the metal band, and an L-shaped groove cast in the glass. The liability of finding the glass irregular instead of circular, after annealing, renders this method unsatisfactory. They have also been secured by holding-devices, catching under the lower edge of the glass; but such a device I am unable to use, for the reason that it is necessary that I should insert my glass within the rim of the base, for the purpose heretofore stated. I therefore employ an indentation, which is in every way satisfactory.

It is the spring-catch which I employ. It is located beneath the flange b, and is secured at one end to the band a. At its free end it has a projecting lip, k, which projects through a slot made in the band a, and is free to engage in the groove j, or its equivalent indentation, at the proper time. In manufacture, I propose to place this lip upon the edge of the locking-spring H, and thus dispense with the use of one spring, and requiring but a single spring throughout the whole lantern. This retaining-groove and spring might be located at the top of the glass, but, as a matter of convenience and economy, I prefer to locate them at the bottom, as shown.

The base or bottom, B, is composed of two parts, the plate f, which forms the base-plate, and the wall, which is divided into three parts, viz; the part h, which I call the band; the bead y, which forms a stop, and limits the distance of the lap of the bands a and h, when the bottom, B, is placed in position in the guard-frame; and the part g, between the bead and base-plate f, to increase the depth of the bottom. Perforations for the admission of air are made through the part g, and also through the base-plate f, if desired. When referring to the bottom, B, it is intended to include the parts f, g, h, and y as a whole.

It is highly desirable that the oil-pot of a lantern should be made separate and detachable from the bottom, so that it may be readily detachable for the purposes of repair and cleansing, and so that the interior of the base or bottom, B, may be easily accessible for the same purpose. It is also desirable that the oil-pot should not be inserted through the base-plate f, but should be placed within the base or bottom, B, from above, because if it is inserted from below upward, through the base-plate f, extra fastenings must be provided, which not only increase the cost of the lantern, but increase the liability of derangement also. I therefore, in forming the base-plate f, make a slight depression, p, in its middle portion, into which the bottom of the oil-pot G fits, and by which the oil-pot is kept in proper position within the bottom.

It is also desirable, in making a lantern for public use, that it should be constructed with the least possible number of detachable or working parts, and that, so far as possible, several duties shall be imposed upon each part, thereby rendering the cost of manufacture less, and also decreasing the liability to derangement in the hands of careless or unskillful people. It is further necessary that the burner-shaft should project through the side of the case, so that the wick may be adjusted without opening or uncovering any part of the lantern. Now, the bottom and guard-frame of a lantern have hitherto been partially secured together by use of the burner-shaft. I secure the bottom, B, to the guard-frame by use of the burner-shaft F alone, the same being made of sufficient length to engage with both sides of the bands a and h, as shown in figs. 2 and 5. The band a is provided with the ordinary L-shaped slot, peculiar to the bayonet-joint, and the band h may also be provided with similar slots; but I prefer to use in the band h, on one side, a rectangular perforation, v, (shown by red line in fig. 13) and, on the other side, a notched slot, q, the shaft springing up into the notch r. A retrograde movement in the slot is thereby prevented. When the shaft F lies in the slots q and v, in the band h, it is quite apparent that the oil-pot will be thereby confined in its seat, p; and as the parts are so proportioned as to compel a slight deflection of said shaft when being placed in the slots in the band h, the elasticity of said shaft will cause it to press upward in said slot, and rest in the notch r, when the same is reached. The function of retaining the oil-pot in its seat will be accomplished even if the opening v should be omitted, and an inward projection substituted, under which the end of the shaft should engage; or if it should be considered objectionable, for any reason, to use the burner-shaft to retain the oil-pot in its seat, the same might be accomplished by some other convenient and well-known device, to bear upon the upper side or cover of the oil-pot, that being considered the most desirable point of attachment.

In order to use the shaft F to retain the oil-pot in place, and also to secure a good attachment to hold the bottom B and frame A securely together, I make the said shaft long enough to extend through both sides of the band a, and consequently, when the oil-pot is in position, and the said shaft properly within the slots q and v, its projected ends will serve as points of attachment for the bayonet-slots t and w of the band a, and the locking-spring H being provided, prevents any change of relative position between the shaft F and band a. If, however, the forms and proportions of the parts should cease with the foregoing description, there might be a liability of turning the bottom, B, so as to release the slot q from the burner-shaft, and permit the bottom, B, to be detached. I therefore make that part, s, of the band a which is beneath the horizontal portions of the slots t and w, of sufficient width to retain the shaft F within the notch r. This is clearly shown in fig. 13, the portion s there filling the space between the bead y and shaft F. In addition to the above functions of the burner-shaft

there may be another, viz, to secure the burner itself in place upon the oil-pot, and this is simply the result of the construction already described, when the burner is secured by simple pressure, instead of by a screw-thread, as in the ordinary manner. This last is, however, a matter of taste. I consider it unobjectionable, but others may prefer to have the burner secured by a screw-thread. In figs. 8 and 9, the red line *x* indicates the proposed position of the lip to engage with the shoulder *j*, to retain the globe in place.

Supposing the parts of my lantern to be all detached, and I am about to assemble them, the guard-frame *A* is taken in one hand and the glass in the other. The glass is inserted within the guard-frame until the spring *I* engages, as described, with the shoulder *j*. It is then securely fastened. I next place the oil-pot in its seat, *p*, and place the burner in position, with the shaft *F* resting within the slots *q* and *v*. One end of the said shaft is then slightly depressed, and by a slight rotation of the shaft in respect to the band *h*, said shaft is brought to the notch *r*. The final operation is to couple the bottom and guard-frame together, and this is done by slipping the band *h* within the band *a*, the burner-shaft *F* passing into the slots *t* and *w*, and the lock-spring *H* securing the whole firmly and securely together. In lanterns of cheap construction, the flanges *b* and *c* are frequently omitted, the ends of the guard-wires *e* being secured directly to the band *a* and cap *d*.

Having described my invention, what I claim as new, and desire to secure by Letters Patent, is—

1. An inwardly-projecting flange around the base or top of a lantern-glass, substantially as and for the purpose set forth.
2. A shoulder or depression in the side of the lantern-glass, in combination with a spring or automatic catch, to lock and retain the globe within the guard-frame, substantially as set forth.
3. Holding a movable lamp or oil-pot down in its proper place upon the base-plate *f*, by means of the burner-shaft.
4. Securing the bottom, *B*, and the guard-frame *A* to each other, by passing the burner-shaft *F* through both of the bands *a* and *h*, and at opposite sides of the lantern, substantially as set forth.
5. In combination with the burner-shaft *F*, extending through both sides of the bands *a* and *h*, and securing the bottom, *B*, and guard-frame *A* together, a spring-catch, *H*, substantially as and for the purpose set forth.
6. In combination with the burner-shaft *F* and slot *q*, or its equivalent, the notch *r*, substantially as and for the purpose set forth.
7. Holding a burner down in its proper place by means of the burner-shaft, secured to both sides of the band *h*, substantially as set forth.
8. Projecting the lower end of the lantern-glass *C* downward within the band *h*, substantially as and for the purpose set forth.
9. The combination of the burner-shaft *F*, secured at each end to the band *h*, with the top of the lamp-pot *G*, in such a manner that the said burner-shaft shall, when in position, be slightly bent or sprung, so as to produce a pressure upon the burner *E* and lamp *G* sufficient to retain them respectively in their places, substantially as herein specified.
10. Fastening a movable lamp-pot, which rests on the bottom of the lantern without any part extending through the same, down in its place, by means of a fastening bearing upon its top, as set forth.
11. A seat, *p*, formed in the base-plate *f*, to retain the movable lamp-pot in a central position, substantially as set forth.

A. G. SMITH.
